UNITED STATES PATENT OFFICE

PHILIP X. RICE, OF DANVILLE, ILLINOIS, ASSIGNOR TO THE MILLER TRAIN CONTROL CORPORATION, OF STAUNTON, VIRGINIA, A CORPORATION OF VIRGINIA

INDUCTOR FOR TRAIN CONTROL SYSTEMS

Application filed April 26, 1926. Serial No. 104,801.

This invention relates to train control systems and more particularly to inductors or track elements for induction train control systems.

5 An object of the present invention is to provide an inductor for use on inductive train control systems that is capable of operating in conjunction with locomotive apparatus or systems of different types.

10 Among the most frequently used inductive train control systems now known are the alternating current system described and claimed in my copending application filed May 3rd, 1926, Serial No. 106,478, and the 15 auto manual direct current unidirectional flux, motional-dynamic system of the General Railway Signal Company. The unidirectional flux type mentioned comprises a magnetized receiver-generator carried on the vehicle, and a track armature or inductor of iron over which the receiver moves. The receiver-generator has a generating winding adapted to generate an electric voltage cycle when passing over said track armature, this 25 result being due to the motional-dynamic phenomena which occurs whenever a magnet has the reluctance of its magnetic path suddenly altered.

Each of these systems employs an inert 30 track element, that is a track element formed of magnetizable metal which will cause a change in the receiver carried by the locomotive, and which is provided with means, such as a coil or coils, to permit the receiver to 35 pass over the track element without being affected when a clear condition exists in the block.

In railway practice trains equipped with 40 one type of train control mechanism frequently travel over tracks of another railroad which may be equipped with another system of train control, and by means of the inductor forming the subject matter of the present invention either type of locomotive apparatus 45 may be actuated to stop the train if danger conditions exist or permit it to pass when the block or track is clear.

In the accompanying drawings I have 50 shown one embodiment of the invention. In this showing—

Figure 1 is a side elevation of a locomotive equipped with a train control apparatus of the type described and claimed in my copending application referred to above,

55 Figure 2 is a diagrammatic perspective view of the universal inductor forming the subject matter of the present invention and also showing, in dotted lines, locomotive apparatus of the motional unidirectional flux type referred to above, and

60 Figure 3 is a similar view showing the locomotive carried apparatus of Figure 1 in position over an ordinary inductor.

65 Referring to the drawings the reference numeral 1 designates generally a locomotive which is mounted on wheels 2 and adapted to travel on a track 3 in the usual manner. The train control system described and claimed in my copending application employs alternating current on the vehicle which may be 70 obtained from a generator 4 or other source to energize a primary coil of a receiver 5. This receiver is an open core transformer adapted to have its secondary voltage and current controlled by flux-directional effect 75 of railroad-side inductors in a manner to be described. The secondary current of the receiver normally retains an electro pneumatic valve in box 6 in a closed position and this valve in turn controls a pneumatically oper- 80 ated brake valve actuator 7.

85 In the motional unidirectional flux type of vehicle carried apparatus there is provided an iron core 8 forming the receiver and having a primary coil 9. This primary coil is energized from a source of current 10 which is connected thereto by lead wires 11 and causes the iron core 8 to become a magnet of unidirectional polarity. Adjacent the other end of the core there is provided a coil 12 which 90 is connected to a relay 13 adapted to actuate the train control mechanism (not shown). The relay is normally held in closed or proceed position from a source of energy 12' and as long as this current remains unneutralized the relay remains closed. The unidirectional flux flowing to the secondary coil 12 from the primary coil 9 has no effect 95 on the latter.

100 Referring to Figure 3 of the drawings

wherein the alternating flux type of receiver is more clearly illustrated, the receiver consists of a pair of rods or plates 14 which are normally spaced from each other. Coils 15 and 16 are connected to two diagonally opposite ends of the two plates and these coils are connected to the source of current 4 by lead wires 17. The other ends of the coils are connected to each other by a wire 18 and a back yoke 19 is arranged between the two rods. The said diagonally opposite ends of the two rods thus form poles 20 and 21 of the primary coil. The other two ends of the rods or plates are likewise provided with coils 22 and 23 which are connected to the train control apparatus, described as a valve magnet 24, by lead wires 25. These two coils are connected at their opposite ends by a suitable connection 26 and thus form secondary poles 27 and 28.

As described in my copending application heretofore referred to, current flowing through the primary coil creates a magnetic flux which normally flows from pole 20 to pole 28 thence through the back yoke 19 to the pole 27, thence to pole 21, and back to the primary pole through the back yoke. The track-side element or inductor heretofore employed in connection with this type of receiver for the purpose of reversing the direction of flow of the magnetic flux consists of a pair of spaced laminated plates 29 arranged beside the track and adapted to be disposed beneath the corresponding plates of the receiver when the locomotive passes over it. These plates or cores are provided with suitable coils 30 connected by lead wires 31 to a condenser 32. A relay switch arm 33 is arranged in the connecting wires 31 and is adapted to be held in closed position by a line relay (not shown) when the block is clear. Briefly, when passing over an open circuited track element the proximity of the plates 29 to the receiver causes the flux to flow from the pole 20 of the primary coil to the upper inductor plate 29 as indicated by the arrows 34 thence through this member to the secondary pole 27 of the receiver, thence through the receiver to the pole 28, thence to the lower inductor element 29 as indicated by the arrows 35, thence through this member to the pole 21 of the receiver and thence to its source. It will be seen that the direction of flow through the secondary is thus reversed, the flux flowing from the pole 27 to the pole 28 instead of from the pole 28 to the pole 27. This reversal of the flow of flux, or tendency to reverse, either reduces the secondary current to a point where it passes through a zero value or reduces it toward zero to such an amount that it becomes insufficient to hold the control valve 6 in closed position. When the track is clear the condenser 32 reflects the received current to the coils 30 and the normal conditions in the receiver are not affected.

The operation of the type of receiver shown in dotted lines in Figure 2 of the drawings depends upon the movement of the receiver relative to the track element to generate or induce a single cycle of current in the secondary of the receiver if the inductor is in stop condition. In this type of apparatus the current is generated by motion in substantially the same manner as by a dynamo armature in motion. When the receiver 8 passes over a track element the quantity of flux passing through the flux path is increased. For this purpose the track element is provided with a pair of poles 36 and is formed of material of high permeability. Between the poles the inductor is provided with a coil 37 and this coil is connected to a relay switch 38 by a suitable lead wire 39, the switch being controlled by the line relay (not shown) in the usual manner. The switch is adapted to engage a contact 40 carried by a lead wire 41 and connected to the opposite end of the coil. A reactor coil 42 may be arranged in either of these wires. A condenser 43 may be bridged across the reactor coil by suitable lead wires 44.

The inductor shown in Figure 2 is also shown modified to perform the functions of the inductor shown in Figure 3 and to function with a receiver of the alternating flux type. As shown the ends of the trackside element beyond the poles 36 are reduced in cross section as at 45 and provided with suitable coils 46. A second laminated plate 47 is arranged parallel to the member 36 and is provided with coils 48 adjacent each end. The coils of each plate are connected to the coils of the other plate by suitable wires 49 and the ends of the coils are connected to lead wires 50 and 51 which are in turn connected to condensers 52. Beyond the condensers one wire of each pair is provided with a contact 53 and the other wire is connected to a relay switch 54 adapted to be controlled by the line relay (not shown).

The operation of the device will be apparent from the foregoing description. As stated, the magnetic flux generated by the coil 9 of a unidirectional polarity similar to a permanent magnet and the unidirectional flux flowing through the coil 12 is not employed to retain the relay 13 closed, but current from the separate source 12' is employed for this purpose. When this receiver passes over a track element the high permeability of that portion of the core formed by the poles 36 and the connecting section causes a change of flux quantity in the receiver and induces a voltage in coil 12. As the receiver passes beyond the inductor the receiver flux decreases thus inducing a secondary voltage reverse to the first mentioned induced voltage. One or the other of these induced voltages is employed to neutralize the steady unidirectional relay current thus allowing the relay

to open to actuate the train control mechanism. To give a clear signal the coil 37 is employed to choke out flux variations in the inductor. With the switch 38 controlled by the line relay in closed position the choke current in the coil 37 and its circuit opposes the normal flux of the receiver and prevents this flux from being changed a sufficient amount to actuate the relay. The reactor coil 42 has no serious effect on the choke current of a (clear) inductor in a system of the unidirectional flux type because of the low frequency employed. This coil is employed for the purpose of preventing the switch 38 from completely short circuiting the clear circuit when high frequency currents are induced by the alternating flux type of receiver shown in Figure 3 of the drawings.

The operation of the alternating flux type of receiver has been described in connection with Figure 3 of the drawings and when employed in connection with the inductor shown in Figure 2, the operation is essentially the same. If the receiver shown in Figure 3 of the drawings passes over the inductor with the contacts 54 in open position the flux from the pole 20 passes through the plate or core 47 and returns to the receiver through the secondary pole 27 thus reversing the normal direction of flow in the secondary of the receiver. When the track is clear and the contacts 54 are closed by the line relay the condensers 52 reflect the current through the coils 46 and 48 preventing any change in the normal flow of current through the receiver.

As stated the reactor coil 42 prevents the coil 37 and its condenser 43 from being short circuited when excited by high frequency energy from a receiver of the alternating flux type but does not prevent it from becoming short circuited when excited by the low frequency cycle employed in the unidirectional system.

It is to be understood that the form of my invention herewith shown and described is to be taken as a preferred example of the same and that various changes in the shape, size, and arrangement of parts may be resorted to without departing from the spirit of the invention or the scope of the subjoined claims.

I claim:

1. A track element for train control systems comprising an inductor adapted to cause generation of current in a coil of a vehicle carried receiver of the unidirectional flux type by virtue of motion of said receiver with respect to said inductor, said inductor having cores parallel to the cores of a receiver of the alternating flux type and being adapted to redirect the flow of flux through said alternating flux receiver.

2. A track element of the character described in claim 1 wherein coils are arranged

on said inductor and adapted to render said inductor inoperative.

3. A track element for train control systems comprising an inductor formed of a pair of cores, one of said cores being provided with a portion of high permeability and adapted to generate current in a vehicle carried receiver of the unidirectional flux type by virtue of movement of said receiver with respect to said inductor, the remaining portion of said core and the other core being adapted to redirect the flow of flux through the cores of a receiver of the alternating flux type.

4. A track element for train control systems comprising an inductor formed of a core of high permeability and adapted to generate current in a vehicle carried receiver of the unidirectional flux type by virtue of movement of said receiver with respect to said inductor, said core being provided with ends of reduced cross-section, a second core of smaller cross sectional area than said first mentioned core, the end portions of said first mentioned core and said second core being adapted to redirect the flow of flux through the cores of a receiver of the alternating flux type, coils arranged on the ends of each core, and condensers connected to said coils whereby a receiver of the alternating flux type may be rendered inoperative in respect to initiation of brake application or speed reduction when said coils are connected to said condensers.

5. A device constructed in accordance with claim 3 wherein the portion of said first mentioned core of high permeability is provided with a coil arranged in a closed circuit and a reactor coil is arranged in said circuit.

6. A device constructed in accordance with claim 3 wherein the first mentioned portion of said inductor is relatively short and elevated and the second mentioned portion thereof is relatively long and depressed.

7. In a train control system of the intermittent inductive type, a track element adapted to influence car-carried receivers either of the uni-directional flux type or of the alternating flux type, and comprising, a magnetic core acting to generate a voltage in the coil of the receiver of the uni-directional flux type by virtue of the movement of the receiver over said magnetic core, said core also acting to change the flux in the core of the receiver of the alternating flux type, and means for rendering the core of said track element ineffective to influence said receivers of either type and comprising control circuits automatically closed under safe traffic conditions and opened under danger traffic conditions, one of said circuits including a condenser.

In testimony whereof I affix my signature.
